(57) **ABSTRACT**

An illumination device 10 includes a reel 13a, a roulette wheel 14c, a motor 14i, an LED tape 14bb, a light guide plate 14e, and a control unit 16. The roulette wheel 14c is provided to the reel 13a and has first graphics formed thereon. The center of rotation of the motor 14i is the center of the roulette wheel 14c. The LED tape 14bb is provided on the front side of the roulette wheel 14c and emits light. The light guide plate 14e is provided on the front side of the roulette wheel 14c, and the light emitted from the LED tape 14bb is incident thereon. The control unit 16 controls the LED tape 14bb so as to switch between a display produced by the light guide plate 14e and a display of the first graphics on the roulette wheel 14c by lighting or not lighting the incident surface of the light guide plate 14e, according to the state of play on a gaming machine 20.

ILLUMINATION DEVICE AND GAMING MACHINE EQUIPPED WITH SAME

CROSS-REFERENCE TO RELATED APPLICATIONS

This application claims priority to Japanese Patent Application No. 2022-080020 filed on May 16, 2022. The entire disclosure of Japanese Patent Application No. 2022-080020 is hereby incorporated herein by reference.

BACKGROUND

Technical Field

The present invention relates to an illumination device installed, for example, in a gaming machine located in a casino or other such gaming facility, as well as to a gaming machine provided with this illumination device.

Description of the Related Art

In recent years, illumination devices that give effects using light sources such as LEDs (light emitting diodes) have been installed around gaming machines in casinos and other such amusement facilities.

For example, Patent Literature 1 discloses a topper device for a gaming machine in which, when there is a win on one of the slot machines constituting a linked system, a win signal is transmitted from the winning slot machine to an installed topper device, and upon receiving this winning signal, the topper device sends an effect signal indicating that a slot machine has won to the other linked topper devices, and executes an effect that guides a position of the winning slot machine by using the topper liquid crystal panel or LED.

Patent Literature

Patent Literature 1: JP-A 2009-028132

SUMMARY

Problem to be Solved by the Invention

However, the following problems are encountered with the above conventional topper device for a gaming machine.

The illumination device included in the gaming machine topper device disclosed in the above publication is installed on the upper part of a slot machine or other such gaming machine, and various effects are produced by combining a liquid crystal panel that displays various effect screens with LEDs that are provided around the liquid crystal panel, so a problem with this configuration is that the effect ends up being uniform and flat.

It is an object of the present invention to provide an illumination device with which a three-dimensional and distinctive effect can be obtained, as well as a gaming machine equipped with this illumination device.

Means for Solving Problem

The illumination device according to the first invention is an illumination device installed in a gaming machine, comprising: a housing unit, a disk-shaped member, a first rotary

drive unit, a first light source unit, a light guide plate, and a first display control unit. The disk-shaped member is provided in the housing and has a first graphic formed on its front surface. The first rotary drive unit rotates the disk-shaped member as a center of rotation of a center of the disk-shaped member. The first light source unit is provided on the front side of the disk-shaped member in the housing unit, and emits light in a specific direction. The light guide plate is provided on the front side of the disk-shaped member in the housing unit, and has an incident surface on which light emitted from the first light source unit is incident, and an exit surface from which the light incident from the incident surface is emitted. The first display control unit controls the first light source unit so as to switch between a display produced by the light guide plate and a display of the first graphics on the disk-shaped member by lighting or not lighting the incident surface of the light guide plate, according to the state of play on the gaming machine.

Here, for example, in an illumination device that is installed in a gaming machine located a casino or other such gaming facility and produces various effects, a light guide plate that performs a desired display when light is incident thereon from the first light source unit is disposed on the front side of a disk-shaped member on which roulette or other such first graphics are drawn, and the lighting of the light guide plate is switched according to various conditions such as the state of play on the gaming machine.

Here, the disk-shaped member has a roulette pattern or the like displayed on it, and is rotationally driven according to the state of play on the gaming machine.

The first light source unit is an LED (light emitting diode), for example, and irradiates the incident surface of the light guide plate with light.

The light guide plate is disposed so as to cover the front side of the disk-shaped member, for example, produces the desired display by means of incident light from the first light source unit, and transmits light when no light is incident, so that the first pattern on the disk-shaped member on the rear side can will be visible.

Consequently, the desired display can be produced on the light guide plate by causing the light from the first light source unit to be incident on the incident surface of the light guide plate, and the first light source unit can be turned off so that the light goes through the light guide plate and the first pattern on the disk-shaped member disposed on the back side of the light guide plate can be displayed.

This allows for switching between a display produced by the light guide plate and a display of the first pattern on the disk-shaped member by switching the lighting of the first light source unit.

As a result, a three-dimensional and distinctive effect can be obtained.

The illumination device according to the second invention is the illumination device according to the first invention, wherein, on the first side surface, the first display control unit causes a second graphic to be displayed by the light reflected by a plurality of prisms that are disposed in a specific pattern on the light guide plate and reflect, in a specific direction, the light emitted from the first light source unit onto the incident surface when the first light source unit is controlled so as to irradiate the light guide plate with light, and causes the first graphic of the disk-shaped member disposed on the back side of the light guide plate to be displayed through the light guide plate when the first light source unit is controlled so as not to irradiate the light guide plate with light.

Consequently, because light is made to be incident on the incident surface of the light guide plate, the plurality of prisms formed on the light guide plate reflect the light inside the light guide plate, and the desired second graphic can be displayed while hiding the first graphic of the disk-shaped member disposed on the back side of the light guide plate. By turning off the first light source unit, the first graphic of the disk-shaped member disposed on the back side of the light guide plate can be displayed through the light guide plate.

The illumination device according to the third invention is the illumination device according to the first or second invention, wherein the decorative illumination unit further has a second light source unit that is disposed on the back side of the disk-shaped member and emits light toward a part of the disk-shaped member, and the illumination device further comprises a second display control unit that controls the second light source unit so as to display part of the graphic of the disk-shaped member.

Consequently, the second light source unit disposed on the back side of the disk-shaped member is lit according to the state of game play on the gaming machine, for example, so part of the disk-shaped member can be irradiated, and only a part of the first graphic can be highlighted in the display.

The illumination device according to the fourth invention is the illumination device according to the third invention, wherein the first display control unit controls the first light source unit to irradiate the light guide plate with light on the first side surface, and causes a second graphic to be displayed by the light reflected by a plurality of prisms that are disposed in a specific pattern on the light guide plate and that reflect, in a specific direction, the light emitted from the first light source unit onto the incident surface, and in this state, the second display control unit controls the second light source unit to display part of the graphic on the disk-shaped member, whereupon a part of the first graphic on the disk-shaped member is displayed on the first side surface through a part of the second graphic.

Consequently, in a state in which light is incident on the light guide plate and the second graphic is displayed on the light guide plate, if, for example, the second light source unit disposed on the back side of the disk-shaped member is lit at a higher quantity of light than the first light source unit, the light will pass through part of the disk-shaped member while also passing through the second graphic of the light guide plate, so that just a part of the first graphic can be highlighted in the display.

The illumination device according to the fifth invention is the illumination device according to the first or second invention, wherein the decorative illumination unit further has a fifth light source unit that emits light onto the surface of the first graphic of the disk-shaped member, and a fifth display control unit that controls the fifth light source unit so as to irradiate the surface of the first graphic with light in a state in which the first display control unit controls the first light source unit so as not to irradiate the light guide plate on the first side surface, and the first graphic of the disk-shaped member disposed on the back side of the light guide plate is displayed through the light guide plate.

Consequently, because the surface of the first graphic is irradiated with light from the fifth light source unit, the light will pass through the light guide plate in a state in which the light guide plate is not being irradiated with light, which makes the first graphic easier to see on the disk-shaped member disposed on the back side of the light guide plate.

The illumination device according to the sixth invention is the illumination device according to the first or second

invention, further comprising a rotating body that has a substantially cylindrical shape and rotates around a rotation axis, and that has a substantially circular first side surface, a second side surface that is disposed opposite the first side surface, and an outer peripheral surface that connects the first side surface and the second side surface, and a second rotary drive unit that rotates the rotating body around a substantially cylindrical center shaft, wherein the housing unit is the rotating body, and the disk-shaped member is provided on a side of the first side surface of the rotating body.

Consequently, for example, a rotating body such as a reel for a jackpot lottery can be rotated, and because the disk-shaped member is provided rotatably to the rotating body, an effect can be produced by the rotation of the rotating body or the disk-shaped member, in addition to the decorative illumination effect produced by the light sources.

The illumination device according to the seventh invention is the illumination device according to the sixth invention, wherein the decorative illumination unit further has a design sheet that is provided on a side of the second side surface of the rotating body, has a specific graphic formed thereon, blocks light from the second side surface, and transmits light from the first side surface.

Consequently, a design sheet having a half-mirror function, which blocks light from the second side surface and transmits light from a side of the first side surface, is disposed on the second side surface on the opposite side from the first side surface on which the light guide plate and the like are disposed in the substantially cylindrical rotating body, which allows for a different display on a side of the second side surface than that on a side of the first side surface.

The illumination device according to the eighth invention is the illumination device according to the seventh invention, further comprising a reflector that is disposed on the back side of the design sheet when viewed from a side of the second side surface, and reflects light from the design sheet side.

Consequently, because a reflector with a reflective function is disposed on the back side of a design sheet having a half-mirror function, the design sheet and the reflector can be used to create a display that functions as an infinity mirror.

The illumination device according to the ninth is the illumination device according to the eighth invention, wherein the decorative illumination unit further has a third light source unit that is provided in a space between the design sheet and the reflector inside the rotating body and emits light in the desired direction, and a third display control unit that controls the third light source unit so as to switch the light on or off.

Consequently, the light emitted from the third light source disposed between the design sheet and the reflector can produce a display with depth when viewed from a side of the second side surface.

The illumination device according to the tenth invention is the illumination device according to the ninth invention, wherein the reflector reflects the light emitted from the third light source unit toward the second side surface, and the light reflected by the reflector is transmitted through the design sheet provided on a side of the second side surface.

Consequently, the light emitted from the third light source unit is reflected by the reflector and is transmitted from the second side to the outside through the design sheet having a half-mirror function, and this creates an effect as an infinity mirror on a side of the second side surface.

The illumination device pertaining to the eleventh invention is the illumination device pertaining to the sixth inventions, wherein the decorative illumination unit further has a fourth light source unit that emits light from the inner peripheral surface side of the rotating body, and the illumination device further comprises a fourth display control unit that controls the fourth light source unit so as to display a specific graphic on the outer peripheral surface of the rotating body.

Consequently, because light from the fourth light source is emitted toward the outer peripheral surface of the substantially cylindrical rotating body, a specific graphic can be displayed on the outer peripheral surface of the rotating body according to the state of game play on the gaming machine, for example.

The illumination device according to the twelfth invention is the illumination device according to the sixth invention, further comprising a base portion that supports the rotating body so as to be rotatable by the first rotary drive unit, and a third rotary drive unit that rotates the rotating body supported by the base portion around a rotary shaft disposed along a substantially vertical direction.

Consequently, because the rotating body is rotated with respect to the base portion that supports the rotating body, the orientation of the rotating body can be switched so that the first side surface, the outer peripheral surface, and the second side surface of the rotating body will be facing a player who is playing a game in front of the gaming machine, for example.

The illumination device pertaining to the thirteenth invention is the illumination device pertaining to the sixth inventions, wherein the rotating body includes a first lottery unit for performing a jackpot lottery, on its substantially cylindrical outer peripheral surface.

Consequently, a jackpot lottery can be performed with a first lottery unit provided on the outer peripheral surface of the substantially cylindrical rotating body according to the state of game play on the gaming machine, for example.

The illumination device pertaining to the fourteenth invention is the illumination device pertaining to the first or second invention, wherein the first graphic of the disk-shaped member includes a second lottery unit that performs a jackpot lottery.

Consequently, a jackpot lottery can be performed with the second lottery unit, such as a roulette wheel, provided on the surface of the disk-shaped member, according to the state of game play on the gaming machine, for example.

The illumination device pertaining to the fifteenth invention is the illumination device pertaining to the first or second invention, further comprising an effect lottery unit that performs a lottery to determine the content of the effect when a jackpot signal is received from the gaming machine.

Consequently, because a jackpot signal is received from the gaming machine and is used to determine by lottery what kind of effect is to be produced in the illumination device, many different effects can be produced in the illumination device according to the game content.

The gaming machine according to the sixteenth invention comprises the illumination device according to the first or second invention, a housing unit in which the illumination device is installed, a display unit that is provided on the front surface of the housing unit to indicate a game state, and an operation deck that is provided on the front of the housing and at the lower part of the display unit, and on which operation inputs made by a player are performed.

Consequently, it is possible to construct a gaming machine equipped with an illumination device capable of

enhancing the effects by means of various three-dimensional displays according to the state of game play on the gaming machine.

Effects

A three-dimensional and distinctive effect can be obtained with the illumination device according to the present invention.

BRIEF DESCRIPTION OF THE DRAWINGS

FIG. 1 is an overall oblique view of the configuration of a gaming machine equipped with the illumination device according to an embodiment of the present invention;

FIG. 2 is a control block diagram of the illumination device in FIG. 1;

FIGS. 3A, 3B, and 3C are oblique views of a configuration in which the orientation of the illumination device in FIG. 1 is switched so that an infinity mirror unit, the outer peripheral surface of a reel, and a roulette unit, respectively, are facing the front;

FIGS. 4A, 4B, and 4C are detail oblique views of the illumination device disposed in the orientations corresponding to FIGS. 3A, 3B, and 3C;

FIG. 5 is a partial cross-sectional view showing a motor for switching the orientation of the illumination device as shown in FIGS. 3A, 3B, and 3C;

FIG. 6A is a partial cross-sectional view of the illumination device in FIG. 1 as seen from above, and FIG. 6B is a partial cross-sectional view thereof as seen from the side;

FIG. 7 is an exploded oblique view of the illumination device in FIG. 1;

FIG. 8 is an exploded oblique view of an infinity mirror unit included in the illumination device of FIG. 7;

FIG. 9A is a front view of the infinity mirror unit side, and FIG. 9B is a cross-line sectional view along the A-A line in FIG. 9A;

FIG. 10A is a diagram showing a state in which an LED is turned off, as a display on the infinity mirror unit side, and FIG. 10B is a diagram showing a state in which an LED is turned on, as a display on the side of the infinity mirror unit.

FIG. 11 is an exploded oblique view of a reel unit included in the illumination device in FIG. 7;

FIG. 12 is an exploded oblique view of a roulette unit included in the illumination device in FIG. 7;

FIG. 13 is an exploded oblique view showing a more detailed configuration of the roulette unit in FIG. 12;

FIG. 14A is a front view of the roulette unit side, and FIG. 14B is a cross-sectional view along the B-B line;

FIG. 15A is a diagram showing a state in which an LED that irradiates the light guide plate with light is turned off, and an LED on the back side of the roulette wheel is turned off, as a display on the roulette unit side, and FIG. 15B is a diagram showing a state in which an LED that irradiates the light guide plate with light is turned off and an LED on the back side of the roulette wheel is turned on, as a display on the roulette unit side; and

FIG. 16A is a diagram showing a state in which an LED that irradiates the light guide plate with light is turned on, and an LED on the back side of the roulette wheel is turned off, as a display on the roulette unit side, and FIG. 16B is a diagram showing a state in which an LED that irradiates the light guide plate with light is turned on, and an LED on the back side of the roulette wheel is also turned on, as a display on the roulette unit side.

DETAILED DESCRIPTION OF THE EMBODIMENT

An illumination device **10** according to an embodiment of the present invention and a gaming machine **20** equipped with this illumination device will be described below with reference to FIGS. 1 to **16B**.

In this embodiment, unnecessarily detailed description may be omitted. For example, detailed description of already known facts or redundant description of components that are substantially the same may be omitted. This is to avoid unnecessary repetition in the following description, and facilitate an understanding on the part of a person skilled in the art.

The applicant has provided the appended drawings and the following description so that a person skilled in the art might fully understand this disclosure, but does not intend for these to limit what is discussed in the patent claims.

As shown in FIG. 1, the illumination device **10** according to this embodiment is mounted on top of a gaming machine **20**, such as a slot machine installed in a casino or other such gaming facility. The illumination device **10** exhibits the effects of illumination and rotation according to the state of game play on the gaming machine **20**.

(1) Configuration of Gaming Machine **20**

The gaming machine **20** comprises a housing unit **21** and an operation deck **22**, as shown in FIG. 1.

The housing unit **21** is a substantially cuboid member, and a display monitor **21a** for displaying the game state is provided on the front side where the player sits.

The display monitor **21a** displays, for example, a plurality of graphics that are rotated and stopped according to operations by the player, and the winning combination is determined by the combination of the graphics when the player's operation causes the graphics to stop. Consequently, the gaming machine **20** awards prizes according to the winning combination determined by the combination of the stopped graphics.

The operation deck **22** is provided on the upper surface of a portion provided so as to protrude toward the player at the lower portion of the housing unit **21**. As shown in FIG. 1, the operation deck **22** is provided with an LCD (liquid crystal display) **22a** and an operation button **22b**.

The LCD **22a** is, for example, a touch panel type of liquid crystal display device, and receives operation inputs from a player who is playing the gaming machine **20**. In this embodiment, an operation for specifying the number of bets from a player playing a slot machine, an operation for rotating lottery graphics, and the like are inputted to the LCD **22a**, for example.

Also, the LCD **22a** is disposed at a position close to the operation button **22b** located adjacent to the operation deck **22** on the right side.

The operation button **22b** is an example of a gaming machine operation button included in the operation deck **22** of the gaming machine **20**. For example, when starting the rotation of lottery graphics displayed on the display monitor **21a**, this button is pressed by the player who is playing the slot machine.

(2) Configuration of Illumination Device **10**

As shown in FIG. 1, the illumination device **10** of this embodiment is installed on the upper surface of the housing unit **21** of the gaming machine **20**, such as a slot machine. When the illumination device **10** receives a signal (such as a jackpot signal) from the gaming machine **20**, the control unit **16** shown in FIG. 2 controls the motors **13e**, **14i**, and **15** and the light source units included in the various constituent

members. More specifically, when the illumination device **10** receives a jackpot signal from the gaming machine **20**, for example, the control unit **16** determines what the effect will be on the basis of the result of the lottery in an effect lottery unit **16b**. Then, the illumination device **10** reads a program stored in the storage unit **16a**, and produces a wide variety of effects by controlling the light source units (LED (light emitting diode) tapes **11d**, **14ba**, and **14bb** and LED boards **13b** and **14j**) and motors **13e**, **14i**, and **15** included in the various constituent members according to the effect that was determined.

More specifically, with the illumination device **10**, as shown in FIGS. 3A, 3B, and 3C, the control unit **16** controls the motor **15** (third drive unit) (see FIG. 5) to rotate the upper surface of the housing unit **21** of the gaming machine **20** around a rotary shaft extending in a substantially vertical direction, thereby switching the orientation. This allows the player who is playing in the gaming machine **20** to select which surface is facing the player from among the front surface (second surface), back surface (first surface), and side surface (outer peripheral surface) of the illumination device **10**, according to the game content at that time, for example.

Also, with the illumination device **10**, a motor **13e** (see FIG. 6B) included in the reel unit **13** (discussed below) rotates a reel **13a** around a substantially cylindrical center shaft. This allows an effect also to be obtained from the rotation of the reel unit **13**.

Furthermore, with the illumination device **10**, a roulette wheel **14c** is rotationally driven by the motor **14i** (see FIG. 6A) included in the roulette unit **14** (discussed below). As a result, a jackpot lottery can be conducted with the roulette unit **14** by spinning and stopping the roulette wheel **14c**.

As shown in FIGS. 4A, 4B, and 4C, the illumination device **10** comprises an infinity mirror unit **11**, a base unit **12**, a reel unit **13**, a roulette unit **14**, and a motor **15** (see FIG. 5).

(2-1) Infinity Mirror Unit **11**

The infinity mirror unit **11** functions as an infinity mirror, and as shown in FIG. 7, is disposed nearest the front surface (second surface) of all the members constituting the illumination device **10**.

As shown in FIG. 8, the infinity mirror unit **11** has a diffuser **11a**, a design sheet **11b**, a cover **11c**, an LED tape (illumination portion) **11d**, a reflector **11e**, and a frame **11f**, in that order starting from the front side.

As shown in FIG. 8, the diffuser **11a** is a light-transmissive, substantially annular member, and is disposed on the outer edge portion on the front side of the infinity mirror unit **11**. The diffuser **11a** is illuminated by the light emitted from an LED **11da** included in the LED tape **11d**, thereby exhibiting a light effect.

As shown in FIG. 8, the design sheet **11b** is a substantially circular sheet that constitutes the front surface of the infinity mirror unit **11**. When the LED **11da** included in the LED tape **11d** is not lit, text or graphics are displayed on the front side of the infinity mirror unit **11**. The design sheet **11b** also has a half-mirror function that does not transmit light from the front side but transmits light from the back side where the LED tape **11d** and the reflector **11e** are disposed.

The cover **11c** is a substantially annular member, and is disposed so as to cover the inner peripheral surface side of the substantially annular LED tape **11d**. The cover **11c** has a plurality of holes **11ca** at positions that are opposite the plurality of LEDs **11da** included in the substantially annular LED tape **11d**.

As shown in FIGS. 9A and 9B, the holes 11ca allow the light emitted from the LED 11da to pass through to the inner peripheral surface side.

The LED tape (decorative illumination unit) 11d is provided in the space between the design sheet 11b and the reflector 11e on the inside of the reel 13a, and emits light in the desired direction. The LED tape 11d is an decorative illumination unit for producing the infinity mirror effect of the infinity mirror unit 11, and has a plurality of LEDs 11da disposed at a specific spacing on the surface of a tape-shaped member.

As shown in FIGS. 9A and 9B, the LEDs (third light source unit) 11da are disposed in groups of three in the width direction of the LED tape 11d. A plurality of these are disposed spaced part in the lengthwise direction of the LED tape 11d. Consequently, the LEDs 11da are used as a light source that produces the infinity mirror effect of the infinity mirror unit 11.

As shown in FIG. 8, the reflector 11e is disposed so as to sandwich the LED tape 11d, etc., between itself and the design sheet 11b, and reflects light on the front side. That is, the reflector 11e reflects the light emitted from the LEDs 11da included in the LED tape 11d toward the front side.

As shown in FIG. 8, the frame 11f is a substantially cylindrical member with a bottom, and as shown in FIG. 9B, is disposed at the outer edge portion on the back side of the infinity mirror unit 11, and holds the reflector 11e, etc., from the back side at the bottom portion of the bottomed substantially cylindrical shape.

With the illumination device 10 of this embodiment, various effects can be produced by the infinity mirror unit 11 disposed on the front side.

More specifically, when the LEDs 11da of the LED tape 11d are unlit, text, graphics, etc., provided on the design sheet 11b are displayed as shown in FIG. 10A.

On the other hand, when the LEDs 11da of the LED tape 11d are lit, the light emitted from the LEDs 11da is transmitted and reflected by the design sheet 11b having a half-mirror function and the reflector 11e. As a result, as shown in FIG. 10B, it is possible to produce a light effect that gives a sense of depth when viewed from the front side of the infinity mirror unit 11.

(2-2) Base Unit 12

The base unit 12 is a member to which the infinity mirror unit 11, the reel unit 13, and the roulette unit 14 are each attached, and as shown in FIG. 7, is disposed so as to be sandwiched between the infinity mirror unit 11 and the roulette unit 14 along with the reel unit 13, out of the members constituting the illumination device 10. The base unit 12 has a substantially cylindrical main body portion, and the reel unit 13 is rotatably disposed on the inner peripheral surface side thereof. The infinity mirror unit 11 is disposed on the front side of the base unit 12, and the roulette unit 14 is disposed on the back side.

The base unit 12 is disposed on the upper surface side of the base portion 12a shown in FIG. 7, and is rotated with respect to the base portion 12a by the above-mentioned motor 15. The base unit 12 is a cylindrical member that is optically transmissive, and includes the reel unit 13 in a rotatable state on its inner peripheral surface side.

As shown in FIG. 7, the base portion 12a is a substantially annular member and is attached to the upper surface of the housing unit 21 of the gaming machine 20. The base unit 12 is rotatably disposed on the upper surface side of the base portion 12a.

(2-3) Reel Unit 13

As shown in FIG. 7, the reel unit 13 is disposed so as to be sandwiched between the infinity mirror unit 11 and the roulette unit 14, along with the base unit 12, among the members constituting the illumination device 10.

The reel unit 13 is disposed on the substantially cylindrical inner peripheral surface side of the base unit 12, and is rotationally driven by the motor 13e to perform a jackpot lottery on the illumination device 10 side according to the lottery result of the effect lottery unit 16b.

As shown in FIG. 11, the reel unit 13 has a reel 13a (rotating body, first lottery unit, housing unit), an LED board 13b (fourth light source unit, decorative illumination unit), a shaft support 13c, a bracket 13d, a motor 13e (second rotary drive unit), and a rotary shaft 13f.

As shown in FIG. 11, the reel 13a (rotating body, first lottery unit, housing unit) is a substantially cylindrical rotating body graphics for performing a jackpot lottery on its outer peripheral surface, and is rotationally driven by the motor 13e provided in the space on the inner peripheral surface side.

The graphics on the outer peripheral surface of the reel 13a include "MAJOR," "GRAND," "SUPER GRAND," "MINOR," and so forth.

As shown in FIG. 11, the LED board 13b (fourth light source unit, decorative illumination unit) is disposed and fixed on the inner peripheral surface side of the substantially cylindrical reel 13a, and emits light from the inner peripheral surface side of the reel 13a. The range of the light emitted from the LED substrate 13b substantially coincides with the size of one of the jackpot lottery graphics that are on the outer peripheral surface of the reel 13a. As a result, when the rotation of the reel 13a stops, the graphics of the reel 13a illuminated by the light from the LED board 13b are used as lottery results, so that a jackpot lottery can be performed on the reel unit 13.

As shown in FIG. 11, the shaft support 13c is fixed to the side surface of the reel 13a using a plurality of screws 13ca, and supports the center of rotation of the reel 13a.

The motor 13e that rotationally drives the reel 13a is attached to the bracket 13d, and the bracket 13d is fixed to the end surface of the rotary shaft 13f using a plurality of screws 13da.

The motor 13e (second rotary drive unit) is a rotary drive source that rotationally drives the reel 13a, and rotates the reel 13a via a plurality of gears such as a reduction gear (not shown). The control unit 16 controls the start and stop of rotation, the rotation speed, the rotation direction, and so on of the motor 13e.

As shown in FIG. 11, the rotary shaft 13f is a substantially cylindrical member that serves as the center of rotation of the reel 13a, and is disposed on the inner peripheral surface side of the reel 13a. The rotary shaft 13f is fixed to the base plate 14a on the roulette unit 14 side by a plurality of screws 13fa.

(2-4) Roulette Unit 14

As shown in FIG. 7, the roulette unit 14 is disposed on the rearmost surface (first surface) side of all the members constituting the illumination device 10. The roulette unit 14 produces various effects with light and rotation for a jackpot lottery on the back side of the illumination device 10.

As shown in FIG. 12, the roulette unit 14 has a base plate 14a, LED tapes 14ba and 14bb, a roulette wheel 14c (disk-shaped member, second lottery unit), a spacer 14d, a light guide plate 14e, a spacer 14f, a transparent cover 14g, and a diffuser 14h.

As shown in FIG. 12, the base plate 14a is a substantially cylindrical member that constitutes the rear surface side of

the roulette unit 14, and holds the LED tapes 14ba and 14bb, the roulette wheel 14c (disk-shaped member, second lottery portion), the spacer 14d, the light guide plate 14e, the spacer 14f, and the transparent cover 14g between itself and the diffuser 14h disposed on the front side of the roulette unit 14.

As shown in FIG. 13, the base plate 14a has a recess 14aa, screw holes 14ab, and screw holes 14ac.

As shown in FIG. 13, the recess 14aa is a recess in which an LED board 14j (discussed below) is attached on the front side of the base plate 14a, and is formed so as to substantially match the size of the LED board 14j.

The screw holes 14ab are through-holes in the base plate 14a, and as shown in FIG. 13, a plurality of screws 14ia for fixing a motor 14i (discussed below) to the back side of the base plate 14a are threaded into these holes.

As shown in FIG. 13, into the screw holes 14ac are threaded a plurality of screws 14ka for fixing a shaft support 14k that rotatably supports the roulette wheel 14c on the front side of the base plate 14a.

As shown in FIG. 12, the LED tapes 14ba and 14bb are decorative illumination units for producing effects in the roulette unit 14, and have a plurality of LEDs disposed at a specific spacing on the surface of a tape-shaped member. The LED tapes 14ba and 14bb are affixed to the inner peripheral surface of the substantially cylindrical base plate 14a and fixed in an annular shape, and a plurality of LEDs that emit light inward in the radial direction are disposed at a specific spacing.

As shown in FIGS. 14A and 14B, the LED tape 14ba (fifth light source unit, decorative illumination unit) is disposed in a substantially annular shape on the outer peripheral side of the roulette wheel 14c, and emits white light, for example, so as to brightly illuminate the surface of the roulette graphics on the roulette wheel 14c. Consequently, the roulette wheel 14c can be displayed in an easy-to-see manner when viewed from the front side of the roulette unit 14.

As shown in FIGS. 14A and 14B, the LED tape 14bb (first light source unit, decorative illumination unit) is disposed at a position on the front side adjacent to the LED tape 14ba, and irradiates the end surface of the light guide plate 14e (discussed below) with light. Consequently, when the LEDs of the LED tape 14bb are lit, a display is performed by the light guide plate 14e, and when the LEDs are not lit, the display can be switched so that the roulette wheel 14c disposed on the back side is displayed through the light guide plate 14e.

As shown in FIGS. 12 and 13, the roulette wheel 14c (disk-shaped member, second lottery unit) is a rotating disk-shaped member having roulette graphics on its front surface, and performs a jackpot lottery in the roulette unit 14. The roulette graphics include, for example, numbers such as "200" and "300" . . . "3000" or characters such as "CHANGE", respectively attached to fan-shaped areas.

As shown in FIG. 12, the spacer 14d is a substantially annular member provided to form a specific gap between the roulette wheel 14c and the light guide plate 14e.

As shown in FIG. 12, the light guide plate 14e is a substantially disk-shaped member that constitutes one of the decorative illumination units that produce light effects in the roulette unit 14, and has an end surface (incident surface) where the light emitted from the LED tape 14bb is incident, and a front surface (exit surface) from which the light incident from the end surface is emitted. The light guide plate 14e is disposed on the front side of the roulette wheel 14c where the roulette graphics are formed. When light from the LED tape 14bb is incident on the end surface of the light guide plate 14e, as shown in FIG. 12, the light guide plate

14e uses the reflection by a plurality of prisms (not shown) provided inside the light guide plate 14e to give a specific display of "BIG DRUM WHEEL" as seen from the front side.

At this point, when the roulette unit 14 is viewed from the front, the light guide plate 14e is disposed on the front side of the roulette wheel 14c. Therefore, in a state in which light is incident on the end surface of the light guide plate 14e from the LED tape 14bb, the roulette graphics of the roulette wheel 14c are hidden by the light guide plate 14e, and the graphics of the light guide plate 14e are displayed. On the other hand, in a state in which the light from the LED tape 14bb is not incident on the end surface of the light guide plate 14e, the roulette graphics of the roulette wheel 14c disposed on the back side are displayed because the light guide plate 14e is transmissive to light.

At this point, since the surface of the roulette graphics is brightly illuminated by the white light emitted from the LED tape 14ba, the roulette graphics can be clearly seen when viewed from the front.

The configuration may be such that one of these light guide plates that function as a shutter for switching between display and non-display of the graphics or the like disposed on the back side is provided to the front of each of the graphics on the outer peripheral surface of the reel 13a described above.

In this case, if a substantially transparent state is created in which light is not allowed to be incident on the incident surface of the light guide plate at the position indicating the lottery result, the lottery result can be displayed, and for the light guide plates at other positions indicating the lottery result, light is allowed to be incident on the incident surface and light is emitted from the exit surface, so the graphics on the reel on the back side can be made invisible.

As shown in FIG. 12, the spacer 14f is a substantially annular member provided to form a specific gap between the front surface of the light guide plate 14e and the diffuser 14h, and is disposed between the light guide plate 14e and the diffuser 14h (see FIG. 14B).

As shown in FIG. 12, the transparent cover 14g is a transparent disk-shaped member that covers the front side of the roulette unit 14, and its outer edge portion is fixed by the diffuser 14h.

As shown in FIG. 12, the diffuser 14h is a substantially annular member that is disposed on the frontmost side of the roulette unit 14 and is transmissive to light, and exhibits a light effect by being lit by the light emitted from the LEDs.

Furthermore, as shown in FIG. 13, the roulette unit 14 has a motor 14i (first rotary drive unit), an LED board 14j (decorative illumination unit), a shaft support 14k, a cover 14l, and a lid 14m.

The motor 14i (first rotation drive unit) is a rotary drive source for rotationally driving the roulette wheel 14c, and as shown in FIG. 13, is fixed with a plurality of screws 14ia. The start and stop of rotation, the rotation speed, the rotation direction, and so forth of the motor 14i are controlled by the control unit 16.

As shown in FIG. 13, the LED board 14j (decorative illumination unit) is attached to a recess 14aa formed on the front side of the base plate 14a. The LED board 14j has a plurality of LEDs 14ja (second light source unit) that emit light from the back side of the roulette wheel 14c onto a part of the roulette graphic stopped at the 12 o'clock position, from among the roulette graphics on the roulette wheel 14c disposed on the front side of the base plate 14a.

As shown in FIGS. 14A and 14B, the LEDs 14ja are disposed on the back side of the roulette wheel 14c, and emit

13

light so as to illuminate the graphic stopped at the 12 o'clock position on the roulette wheel 14c.

Consequently, when the roulette wheel 14c is rotated and stopped, the roulette graphic stopped at the 12 o'clock position can be selected as the lottery result.

As shown in FIG. 13, the shaft support 14k is a member that supports the central portion of the roulette wheel 14c from the front side so as to allow the roulette wheel 14c to rotate, and is fixed to the base plate 14a side by threading a plurality of screws 14ka into screw holes 14ac.

As shown in FIG. 13, the cover 14l is attached so as to cover the shaft support 14k, and is fixed to the shaft support 14k by a screw 14la.

As shown in FIG. 13, the lid 14m is disposed on the frontmost side of all the members constituting the center axis of the roulette wheel 14c, and is attached so as to cover the screw 14la portion of the cover 14l.

(2-5) Motor 15

As described above, the motor 15 is a rotary drive source that rotationally drives the illumination device 10 on the upper surface of the housing unit 21 of the gaming machine 20, and as shown in FIG. 5, is disposed on the lower surface side of the base portion 12a of the base unit 12. The motor 15 rotates the entire illumination device 10 on the upper surface of the housing unit 21 of the gaming machine 20.

Also, the start and stop of rotation, the rotation speed, the rotation direction, and so forth of the motor 15 are controlled by the control unit 16.

Consequently, the motor 15 can switch the orientation of the illumination device 10 so as to orient the infinity mirror unit 11, orient the roulette unit 14 on the opposite side, or orient the reel 13a side of the reel unit 13 on the side thereof, toward a position at the front that is opposite the player who is playing the gaming machine 20.

Also, by continuously rotating the entire illumination device 10 with the motor 15, various effects, such as the infinity mirror effect of the infinity mirror unit 11, or an effect produced by light and the rotation of the reel unit 13 and the roulette unit 14, can be further enhanced.

Light Effect Control by Control Unit 16

With the illumination device 10 in this embodiment, as shown in FIG. 2, the control unit 16 controls the light sources (LEDs 11da, 14ja, etc.) included in the infinity mirror unit 11, the base unit 12, the reel unit 13, and the roulette unit 14 to produce a light effect.

More specifically, the control unit 16 controls the LED tape 14bb so as to switch the display of a plurality of graphics on the substantially circular surface of the reel 13a by allowing or not allowing light to be incident on the incident surface of the light guide plate 14e according to state of game play of the gaming machine 20 (result of a jackpot lottery, etc.), for example.

For example, when the control unit 16 controls the LED tape 14bb so as not to irradiate the light guide plate 14e with light, as shown in FIG. 15A, the light goes through the light guide plate 14e and the roulette graphics of the roulette wheel 14c disposed on the back side of the light guide plate 14e are displayed.

At this point, the LED tape 14ba illuminates the surface of the roulette wheel 14c with white light, so that the roulette graphics on the roulette wheel 14c can be clearly recognized when the roulette unit 14 is viewed from the front.

Also, at this point, the control unit 16 controls the LEDs 14ja of the LED board 14j so that a part of the roulette graphics on the roulette wheel 14c is displayed as the lottery result.

14

In this embodiment, as shown in FIG. 15B, in a lottery with the roulette unit 14, the graphic stopped at the 12 o'clock position of the roulette wheel 14c is illuminated by the LEDs 14ja of the LED board 14j disposed on the back side, and is displayed as the lottery result.

On the other hand, for example, when the control unit 16 controls the LED tape 14bb so as to irradiate the light guide plate 14e with light, as shown in FIG. 16A, a specific graphic is displayed by the light reflected by a plurality of prisms 10 that are arranged in a specific pattern on the light guide plate 14e and reflect, in a specific direction, the light emitted from the LED tape 14bb onto the incident surface.

Consequently, a specific graphic is displayed by light reflected by the plurality of prisms that are arranged in a specific pattern on the light guide plate 14e and reflect, in a specific direction, the light emitted from the LED tape 14bb to the incident surface. In this state, the control unit 16 controls the LEDs 14ja of the LED board 14j so as to display a part of the roulette graphics on the roulette wheel 14c, so that a larger amount of light is emitted than the light from the LED tape 14bb and incident on the light guide plate 14e.

As a result, as shown in FIG. 16B, the light goes through a part of a specific graphic, and a part of the roulette graphics on the roulette wheel 14c is displayed. Therefore, the player 25 of the gaming machine 20 will feel more excitement upon hitting a jackpot lottery because the displayed portion is only the part of the roulette graphics on the roulette wheel 14c that displays the result of the lottery.

At this point, control may be performed to switch between illuminating and not illuminating the end surface of the light guide plate 14e with the light from the LED tape 14bb so as to display or hide the roulette graphics of the roulette wheel 14c while the roulette wheel 14c is rotating.

This allows the player to feel even more excitement while 35 waiting for the lottery result on the roulette unit 14.

Furthermore, if the control unit 16 controls the LED tape 14bb so that light does not irradiate the light guide plate 14e on the surface on the roulette unit 14 side, the roulette graphics on the roulette wheel 14c disposed on the back side 40 of the light guide plate 14e will be displayed through the light guide plate 14e. Then, in this state, the control unit 16 controls the LED tape 14ba so as to irradiate the surface of the roulette graphics with white light.

Consequently, the roulette wheel 14c displayed on the 45 surface on the roulette unit 14 side is brightly illuminated, making it easy for the player playing the gaming machine 20 to see the roulette wheel.

Also, the control unit 16 controls the lighting of the LEDs 11da of the LED tape 11d in order to produce an infinity 50 mirror effect in the infinity mirror unit 11.

This allows switching between the display of the graphic formed on the design sheet 11b shown in FIG. 10A and the light display that provides a sense of depth as an infinity mirror as shown in FIG. 10B.

55 Main Feature 1

The illumination device 10 of this embodiment is installed in the gaming machine 20, and comprises the reel 13a, the motor 13e, the roulette wheel 14c, the motor 14i, and the LED tapes 14ba and 14bb. The reel 13a has a substantially 60 cylindrical shape, rotates around a rotary shaft, and has a substantially circular front surface, a rear surface disposed opposite the front surface, and an outer peripheral surface that connects the front surface and the rear surface. The motor 13e and the reel 13a are rotated around a substantially cylindrical center shaft. The roulette wheel 14c is provided inside the reel 13a when viewed from the rear side, and has roulette graphics formed thereon. The center of rotation of 65

15

the motor **14i** is the center of the roulette wheel **14c**. The LED tapes **14ba** and **14bb** are provided on the reel **13a**, and produce effects with light.

Consequently, by combining the rotation of the reel **13a**, the rotation of the roulette wheel **14c** provided inside the reel **13a**, and the light effect produced by the LED tapes **14ba** and **14bb** provided to the reel **13a**, it is possible to produce a wide variety of effects to match the state of play on the gaming machine **20** without having to use a liquid crystal display panel or the like.

As a result, a three-dimensional and distinctive effect can be obtained.

Main Feature 2

The illumination device **10** of this embodiment is installed in the gaming machine **20**, and comprises the reel **13a**, the roulette wheel **14c**, the motor **14i**, the LED tape **14bb**, the light guide plate **14e**, and the control unit **16**. The roulette wheel **14c** is provided to the reel **13a** and has a first graphic formed on its front surface. The center of rotation of the motor **14i** is the center of the roulette wheel **14c**. The LED tape **14bb** is provided on the front side of the roulette wheel **14c** in the reel **13a**, and emits light in a specific direction. The light guide plate **14e** is provided on the front side of the roulette wheel **14c** in the reel **13a**, and has an incident surface on which light emitted from the LED tape **14bb** is incident and an exit surface from which the light incident from the incident surface is emitted. The control unit **16** controls the LED tape **14bb** so as to switch between a display produced by the light guide plate **14e** and the display of the roulette graphics on the roulette wheel **14c**, depending on whether the incident surface of the light guide plate **14e** is lit or unlit, according to the state of play on the gaming machine **20**.

Here, for example, in the illumination device **10** that is installed in the gaming machine **20** located a casino or other such gaming facility and produces various effects, the light guide plate **14e** that performs a desired display when light is incident thereon from the LED tape **14bb** is disposed on the front side of the roulette wheel **14c** on which the roulette graphics are drawn.

Consequently, the desired display can be produced on the light guide plate **14e** by allowing light from the LED tape **14bb** to be incident on the incident surface of the light guide plate **14e**, and the roulette graphics of the roulette wheel **14c** disposed on the back side of the light guide plate **14e** can be displayed through the light guide plate **14e** by turning off the LED tape **14bb**.

Consequently, switching the light of the LED tape **14bb** on or off allows for switching between a display produced by the light guide plate **14e** and a display of the roulette graphics on the roulette wheel **14c**.

As a result, a three-dimensional and distinctive effect can be obtained.

OTHER EMBODIMENTS

An embodiment of the present invention was described above, but the present invention is not limited to the above embodiment, and various modifications are possible without departing from the gist of the invention.

(A)

In the above embodiment, an example was given in which upon receiving a jackpot signal from the gaming machine **20**, the effect lottery unit **16b** of the control unit **16** determined what kind of effect is to be performed in the illumination device **10**, and based on that determination, controlled the light source units and the motors, thereby

16

producing a wide variety of effects. However, the present invention is not limited to this.

For example, the illumination device may be installed as a single component of the gaming machine and be controlled by the control unit of the gaming machine.

(B)

In the above embodiment, an example was given in which the control unit **16** of the illumination device **10** controlled the lighting of the LED tapes **11d**, **14ba**, and **14bb** and the LED boards **13b** and **14j**. However, the present invention is not limited to this.

For example, the configuration may be such that a separate control unit is provided for each light source unit.

(C)

In the above embodiment, an example was given in which the control unit **16** of the illumination device **10** controlled the rotation of the three motors **13e**, **14i**, and **15**. However, the present invention is not limited to this.

For example, the configuration may be such that a separate control unit is provided for each motor.

(D)

In the above embodiment, an example was given in which the graphics for the jackpot lottery were displayed on the outer peripheral surface of the substantially cylindrical reel (rotating body) **13a**. However, the present invention is not limited to this.

For example, graphics that heighten the player's sense of immersion in the game may be displayed on the outer peripheral surface of the rotating body, rather than those for a jackpot lottery.

(E)

In the above embodiment, an example was given in which the roulette wheel **14c** that was rotationally driven to perform a jackpot lottery was provided on one side surface of the reel (rotating body) **13a**. However, the present invention is not limited to this.

For example, graphics that heighten the player's sense of immersion in the game may be displayed on the surface of the roulette wheel, rather than those for a jackpot lottery.

(F)

In the above embodiment, an example was given in which the infinity mirror unit **11** was disposed on the other side surface of the reel (rotating body) **13a**. However, the present invention is not limited to this.

For example, the decorative illumination unit disposed on the side surface of the rotating body may be a decorative illumination unit having a decorative illumination function apart from the infinity mirror unit.

(G)

In the above embodiment, an example was given in which the design sheet **11b** of the infinity mirror unit **11** displayed the specific characters "OMRON.". However, the present invention is not limited to this.

For example, what is displayed on the design sheet may be other text information, or something else may be displayed, such as a design or image.

(H)

In the above embodiment, an example was given in which a slot machine was used as the gaming machine in which the illumination device **10** was installed. However, the present invention is not limited to this.

For example, the illumination device may be installed in a gaming machine other than a slot machine.

INDUSTRIAL APPLICABILITY

The illumination device of the present invention allows three-dimensional and distinctive effects to be produced, and

17

therefore can be widely applied as an illumination device that is installed in any of various devices.

The invention claimed is:

1. An illumination device installed in a gaming machine, comprising:
  - a housing unit;
  - a disk-shaped member that is provided to the housing unit and has a first pattern formed on a front surface;
  - a first rotary drive unit configured to rotate the disk-shaped member as a center of rotation of a center of the disk-shaped member;
  - a first light source unit that is provided on a front side of the disk-shaped member in the housing unit and configured to emit light in a specific direction;
  - a light guide plate that is provided on a front side of the disk-shaped member in the housing unit and has an incident surface on which the light emitted from the first light source unit is incident, and an exit surface from which the light incident from the incident surface is emitted; and
  - a first display control unit configured to control the first light source unit so as to switch between a display produced by the light guide plate and a display of a first graphics on the disk-shaped member by lighting or not lighting the incident surface of the light guide plate, according to a state of play on the gaming machine.
2. The illumination device according to claim 1, wherein, the first display control unit:
  - causes a second graphic to be displayed by the light reflected by a plurality of prisms that are disposed in a specific pattern on the light guide plate and reflect, in a specific direction, the light emitted from the first light source unit onto the incident surface when the first light source unit is controlled so as to irradiate the light guide plate with light, and
  - causes the first graphic of the disk-shaped member disposed on a back side of the light guide plate to be displayed through the light guide plate when the first light source unit is controlled so as not to irradiate the light guide plate with light.
3. The illumination device according to claim 1, further comprising
  - a second light source unit that is disposed on a back side of the disk-shaped member and configured to emit light toward a part of the disk-shaped member, and
  - a second display control unit configured to control the second light source unit so as to display part of a graphic of the disk-shaped member.
4. The illumination device according to claim 3, wherein the first display control unit controls the first light source unit to irradiate the light guide plate with light, and causes a second graphic to be displayed by the light reflected by a plurality of prisms that are disposed in a specific pattern on the light guide plate and that reflect, in a specific direction, the light emitted from the first light source unit onto the incident surface, and in this state, the second display control unit controls the second light source unit to display part of the graphic on the disk-shaped member, whereupon a part of the first graphic on the disk-shaped member is displayed through a part of the second graphic.
5. The illumination device according to claim 1, further comprising:
  - a fifth light source unit configured to emit light onto a surface of the first graphic of the disk-shaped member; and

18

- a fifth display control unit configured to control the fifth light source unit so as to irradiate the surface of the first graphic with light in a state in which the first display control unit controls the first light source unit so as not to irradiate the light guide plate, and the first graphic of the disk-shaped member disposed on a back side of the light guide plate is displayed through the light guide plate.
6. The illumination device according to claim 1, further comprising:
  - a rotating body that has a substantially cylindrical shape and configured to rotate around a rotation axis, and that has a substantially circular first side surface, a second side surface that is disposed opposite the first side surface, and an outer peripheral surface that connects the first side surface and the second side surface; and a second rotary drive unit configured to rotate the rotating body around a substantially cylindrical center shaft, wherein the housing unit is the rotating body, and the disk-shaped member is provided on a side of the first side surface of the rotating body.
7. The illumination device according to claim 6, further comprising
  - a design sheet that is provided on a side of the second side surface of the rotating body, has a specific graphic formed thereon, blocks light from the second side surface, and transmits light from the first side surface.
8. The illumination device according to claim 7, further comprising
  - a reflector that is disposed on a back side of the design sheet when viewed from a side of the second side surface, and reflects light from a side of the design sheet.
9. The illumination device according to claim 8, further comprising:
  - a third light source unit that is provided in a space between the design sheet and the reflector inside the rotating body and configured to emit light in a desired direction.
10. The illumination device according to claim 9, wherein the reflector reflects the light emitted from the third light source unit toward the second side surface, and the light reflected by the reflector is transmitted through the design sheet provided on a side of the second side surface.
11. The illumination device according to claim 6, further comprising
  - a fourth light source unit configured to emit light from a side of an inner peripheral surface of the rotating body, and
  - a fourth display control unit configured to control the fourth light source unit so as to display a specific graphic on the outer peripheral surface of the rotating body.
12. The illumination device according to claim 6, further comprising:
  - a base portion configured to support the rotating body so as to be rotatable by the second rotary drive unit; and a third rotary drive unit configured to rotate the rotating body supported by the base portion around a rotary shaft disposed along a substantially vertical direction.
13. The illumination device according to claim 6, wherein the rotating body includes a first lottery unit for performing a jackpot lottery, on its substantially cylindrical outer peripheral surface.

14. The illumination device according to claim 1, wherein the first graphic of the disk-shaped member includes a second lottery unit configured to perform a jackpot lottery.

15. The illumination device according to claim 1, further comprising an effect lottery unit configured to perform a lottery to determine a content of the effect when a jackpot signal is received from the gaming machine. 5

16. A gaming machine, comprising: the illumination device according to claim 1; 10 a housing unit in which the illumination device is installed; a display unit that is provided on a front surface of the housing unit to indicate a game state; and 15 an operation deck that is provided on a front of the housing unit and at a lower part of the display unit, and on which operation inputs made by a player are performed.
